UNITED STATES PATENT OFFICE.

CROMWELL O. CASE, OF NEW BRITAIN, CONNECTICUT, ASSIGNOR TO THE
P. & F. CORBIN, OF SAME PLACE.

LEVER CONNECTION FOR DOOR CHECKS AND CLOSERS.

SPECIFICATION forming part of Letters Patent No. 599,415, dated February 22, 1898.

Application filed July 2, 1897. Serial No. 643,237. (No model.)

To all whom it may concern:

Be it known that I, CROMWELL O. CASE, a citizen of the United States, residing at New Britain, Hartford county, Connecticut, have 5 invented certain new and useful Improvements in Lever Connections for Door-Checks and the Like, of which the following is a full, clear, and exact description.

My invention relates to an improved lever 10 connection for door - checks and the like, among the main objects of the same being the provision of a suitable means whereby cramping or binding upon the check mechanism is avoided when the parts are in operation and 15 the provision of a means whereby lateral motion or slipping of the parts of the lever-arm, which is adjustable as to length, is prevented.

Referring to the drawings, Figure 1 is a a 20 plan view. Fig. 2 is a sectional detail of one of the connections, showing the end of one of the sections of the adjustable lever-arm in connection therewith. Fig. 3 is a detail view of the end of the other section of the adjustable lever-arm. Fig. 4 is a section on line $y-y$, Fig. 2, and slightly enlarged. Fig. 5 is a section on line $z-z$, Fig. 3, and slightly enlarged. Fig. 6 is a section on line $x-x$, Fig. 1.

A is a door-easing.

B is a door.

30 C is a door check or closer.

D is a lever-arm carried and operated by the mechanism C. The lever-arm by which the free end of the arm D is connected to the casing A is composed of two sections E and 35 E', the same being adjustable as to length.

F is a clamp, and F' a tightening-screw, by which means the sections E E' are held at any desired position.

G is a journal-bearing ordinarily secured 40 to the casing A. In the rear of the journal G is carried an adjusting screw or plug G², the inner end of the said screw or plug being preferably dished.

G' G' are flanges in the front of the bearing G.

E² is a rounded head at the free extremity of the section E', the said head being of greater diameter than the space between the flanges G' G'.

50 In assembling the parts G E' the plug G² is first removed and the arm E' passed through

the bearing G from the rear until the head E² is seated, as shown in Fig. 2. The plug G² is then replaced, the same affording a means for tightening or loosening the joint at that point. 55

The elbow-joint between the two lever-arms is illustrated in Figs. 1 and 6, in which a ball-bearing E³ is carried by the arm E, a suitable socket being provided in the other arm E', adapted to receive said ball-bearing, the adjustment of the parts being effected by the plug D'. It is manifest that this order of arrangement may be reversed. The abutting faces of the parts D E are rounded, as shown in Fig. 6, to give sufficient universal play. 65 The ball-bearing E³ may be secured to its lever-arm in any desirable manner.

From the above it will be seen that cramping or binding of the check mechanism is avoided.

70

The means by which lateral motion and slipping of the sections E E' are accomplished comprises primarily a longitudinal rib H, carried by one of the sections E E', and a corresponding groove or depression I in the other 75 section, into which said rib H projects. The facing surfaces of the sections E E' may be in addition gnurled or roughened or provided with transverse ribs registering alternately with each other, so as to prevent longitudinal 80 slipping. By this means the effective longitudinal adjustment of this arm is made possible and side motion or slipping of the sections E E' prevented.

While the check C is shown as attached to 85 the door B and the bearing G is shown as attached to the casing, there are instances in which this arrangement may be reversed.

Other changes in detail of construction and arrangement from those illustrated may be 90 made without departing from the spirit and scope of my invention, and it should not be understood that it is my intention to limit myself to the precise arrangement and construction herein shown and described. 95

What I claim is—

In a lever connection for door-checks and the like, a lever-arm adjustable as to length, said arm comprising two sections, a central longitudinal groove in the engaging face of 100 one of said sections, a central longitudinal rib on the other section corresponding to said

groove, flat engaging faces on each side of said groove and rib, said flat faces being provided with alternate transverse ribs and grooves, the transverse ribs in one of said 5 sections registering with the transverse grooves in the other section, and a clamp embracing said sections.

Signed at New Britain, in the county of Hartford and State of Connecticut, this 25th day of June, 1897.

CROMWELL O. CASE.
